DESIGN FOR A DISPLAY RACK FOR NECK- TIES OR THE LIKE

William Seidler, New York, N. Y.

Application December 15, 1939, Serial No. 88,912

Term of patent 3½ years

To all whom it may concern:

Be it known that I, William Seidler, a citizen of Germany and resident of the Borough of Manhattan, city, county, and State of New York, have invented a new, original, and ornamental Design for a Display Rack for Neckties or the like, of which the following is a specification, reference being had to the accompanying drawing, forming part thereof.

Fig. 1 is a perspective view of a display rack for neckties or the like, showing my new design.

Fig. 2 is an end elevational view of the same on a reduced scale.

I claim:

The ornamental design for a display rack for neckties or the like, substantially as shown.

WILLIAM SEIDLER.
